Primary Examiner — Mimosa De

(57) CLAIM

The ornamental design for the seats, as shown and described.

DESCRIPTION

FIG. 1 is an illustration of an isometric view of seats mounted in a golf cart;

FIG. 2 is an illustration of another isometric view of the seats;

FIG. 3 is an illustration of a front view of the seats;

FIG. 4 is an illustration of a right side view of the seats;

FIG. 5 is an illustration of a left side view of the seats;

FIG. 6 is an illustration of a rear view of the seats;

FIG. 7 is an illustration of a top view of the seats; and,

FIG. 8 is an illustration of a bottom view of the seats.

The broken lines in the seats of FIG. 1 represent portions of the seats which are not part of the claimed design. The remainder of the broken lines shown in FIG. 1 represents a golf cart which is not part of the claimed design. The broken lines in FIGS. 2, 4, 5, 7 and 8 represent portions of the seats which are not part of the claimed design. The dot-dash lines in FIGS. 6 and 8 demarcate areas of the seats which are not part of the claimed design.
